US00D990966S

(12) **United States Design Patent** (10) **Patent No.:** **US D990,966 S**
Tehrani et al. (45) **Date of Patent:** **** Jul. 4, 2023**

(54) **COOKWARE LID**(71) Applicant: **Lagom Kitchen Co.**, Culver City, CA (US)(72) Inventors: **Amir Tehrani**, Los Angeles, CA (US); **Zachary Rosner**, Los Angeles, CA (US); **Stuart Harvey Lee**, Forest Hills, NY (US); **Jochen Schaepers**, New York, NY (US)(73) Assignee: **Lagom Kitchen Co.**, Culver City, CA (US)(***) Term: **15 Years**(21) Appl. No.: **29/846,266**(22) Filed: **Jul. 14, 2022****Related U.S. Application Data**

(60) Continuation of application No. 29/825,171, filed on Jan. 28, 2022, which is a continuation of application No. 29/800,803, filed on Jul. 23, 2021, now Pat. No. Des. 972,881, which is a division of application No. 29/748,445, filed on Aug. 28, 2020, now Pat. No. Des. 929,798, which is a continuation-in-part of application No. 29/699,401, filed on Jul. 25, 2019, now Pat. No. Des. 916,547.

CLAIM

The ornamental design for a cookware lid, as shown and described.

DESCRIPTION

FIG. 1 is a top, front perspective view of a cookware lid showing our new design;

FIG. 2 is a right side view thereof, wherein the left side view is a mirror image of FIG. 2;

FIG. 3 is a front view thereof;

FIG. 4 is a rear view thereof;

FIG. 5 is a top view thereof; and,

FIG. 6 is a bottom view thereof.

The broken lines immediately adjacent to the shaded area define the bounds of the claimed design and form no part thereof. The broken lines depicting the remainder of the cookware lid form no part of the claimed design.

1 Claim, 4 Drawing Sheets

FIG. 1

FIG. 2

FIG. 3

FIG. 4

FIG. 5

FIG. 6
